[57] CLAIM

The ornamental design for a kitchen utility rack, as shown and described.

DESCRIPTION

FIG. 1 is a top, front, and left side perspective view of a kitchen utility rack showing my new design;
FIG. 2 is a left side elevational view thereof, the right side being a mirror image of that shown;
FIG. 3 is a top plan view thereof;
FIG. 4 is a front elevational view thereof;
FIG. 5 is a bottom plan view thereof; and,
FIG. 6 is a rear elevational view thereof.
